UNITED STATES PATENT OFFICE.

ROLLIN L. GRAY, OF EAU CLAIRE, WISCONSIN.

HAIRPIN.

1,382,353.

Specification of Letters Patent. Patented June 21, 1921.

Application filed March 6, 1920. Serial No. 363,715.

To all whom it may concern:

Be it known that I, ROLLIN L. GRAY, a citizen of the United States, residing at Eau Claire, in the county of Eau Claire and 5 State of Wisconsin, have invented certain new and useful Improvements in Hairpins, of which the following is a specification.

This invention relates to improvements in hairpins and has as one of its objects to 10 provide a hairpin which may be readily inserted in the hair and readily removed therefrom and which when in place will securely grip the hair encompassed thereby and thus be securely retained in place.

15 Another object of the invention is to provide a hairpin so constructed that as the same is inserted in the hair it will be automatically spread so as to gather and receive a relatively large lock of the hair and 20 which when finally positioned will automatically close so as to grip and tightly confine the hair engaged thereby.

A further object of the invention is to 25 provide a hairpin having portions which normally close the throat of the pin and to so form the terminals of the legs of the pin as to cause automatic spreading or separation of these portions when the pin is inserted into the hair and thus enable the lock 30 of hair engaged by the pin to readily enter the said throat.

In the accompanying drawings:

Figure 1 is a view in side elevation of a hair pin formed in accordance with the 35 present invention;

Fig. 2 is an edge view thereof;

Fig. 3 is a detail fragmentary perspective view of the end portions of the pin.

The hairpin embodying the present invention is, as in the case of the ordinary forms 40 of hairpins now in use, to be formed from a single strand of resilient wire which is bent at a point midway between its ends to provide the legs of the pin which are indicated by the numeral 1, and a connecting or bight portion which is indicated by the 45 numeral 2 and which extends between the upper ends of the said legs. From the connecting portion 2, the legs 1 extend downwardly in parallel relation as indicated by the 50 numeral 3 and below their portions 3 they are bent to extend diagonally inwardly toward each other as at 4 and then formed with bends 5 providing diverging jaw portions 6. At the lower ends of the portions 55

6, the legs are bent inwardly toward each other as indicated by the numeral 7 and are then bent as at 8 to provide diverging jaw portions 9. At the lower ends of the portions 9, the legs are again bent inwardly toward each other as at 10 and are then bent outwardly as at 11 and then are extended in parallel relation as indicated by the numeral 12. Below the parallel portions 12 the legs 1 are bent to extend inwardly as at 13 and 60 14 are then bent as at 15 to provide diverging portions 15. The portions 13 and 15 of the two legs constitute means for closing the throat of the pin which throat is defined by the latter portions, the resiliency of the pin 70 serving to normally yieldably hold the legs 3 in such position that the bends 14 will overlap to about the extent illustrated in Figs. 1 and 3 of the drawings. In order that the terminals of the diverging portions 75 15 may not cause injury to the scalp in applying the pin, these terminals which are indicated by the numeral 16, are bent to extend substantially in alinement with the portions 3 and 12. As above pointed out 80 the pin embodying the invention is resilient and while the throat of the pin is normally closed by the overlapping bends 14 of the closing portions comprising the parts 13 and 15, it will be readily understood that 85 when the pin is inserted in the hair, the legs of the pin will be spread apart against their resiliency by the passage of the hair between the portions 15 and that these portions, because of their diverging relation, 90 will serve to gather a considerable quantity of the hair in applying the pin as well as providing means for automatically spreading the legs and opening the throat of the pin in the act of applying the same. After 95 the pin has been inserted in the hair, the resiliency of the legs will serve to draw the same together so that they will tend to assume the normal position illustrated in Figs. 1 and 3 in which position the bends 14 will 100 again be in overlapped relation closing the throat of the pin and thereby preventing accidental separation of the pin from the hair.

Referring to Fig. 1 it will be observed 105 that the space between the bends 5 is slightly greater than the space between the bends 8 and that, in turn, this latter space is slightly greater than the space between the bends 11, the legs of the pin being in their 110

normal positions. However, when the pin is inserted in the hair and the legs are spread, these bends will be further separated but in such relatively increasing degree in the order in which they are referred to above that all of these spaces will be of substantially the same width while the pin is being inserted and therefore the bends will more readily permit the passage of the hair into the pin, and when the legs of the pin are relieved of tension and are permitted to spring together through their resiliency, the lock or locks of hair encompassed by the pin will be so engaged and confined by the several bends 5, 8 and 11 as to further insure against accidental disengagement of the pin.

Having thus described the invention, what is claimed as new is:

A hairpin comprising resilient legs having spaced parallel upper and lower portions and intermediate portions formed each with a series of bends, corresponding bends in the two intermediate portions being oppositely located, the spaces between the bends being relatively decreased in width in the direction of the free ends of the legs, and the free ends being formed into overlapping bends providing a throat having sharply divergent extremities engaging the hair for opening the throat on insertion of the pin.

In testimony whereof I affix my signature.
ROLLIN L. GRAY. [L. s.]
